UNITED STATES PATENT OFFICE

TRUMAN B. BUCHANAN, OF DENVER, COLORADO

DESIGN FOR A STORE FRONT OR THE LIKE

Application filed November 20, 1930. Serial No. 37,735. Term of patent 14 years.

To all whom it may concern:

Be it known that I, TRUMAN B. BUCHANAN, a citizen of the United States, residing in the city and county of Denver, State of Colorado, have invented a new, original, and ornamental Design for Store Fronts or the Like, of which the following is a specification, reference being had to the accompanying drawings, forming part thereof.

I claim:

The ornamental design for a store front or the like, as shown.

TRUMAN B. BUCHANAN.
